(57) **CLAIM**

The ornamental design for a hair clipper, as shown and described.

DESCRIPTION

FIG. 1 is a top perspective view of a first embodiment of the present design for a hair clipper;

FIG. 2 is a bottom view of same;

FIG. 3 is a side view of same, the left and right sides being mirror images of each other;

FIG. 4 is a top view of the hair clipper of FIG. 1;

FIG. 5 is front view of same;

FIG. 6 is a rear view of same;

FIG. 7 is a top perspective view of a second embodiment of the present hair clipper;

FIG. 8 is a bottom view of same;

FIG. 9 is a side view of the hair clipper of FIG. 8, both sides being mirror images of each other;

FIG. 10 is a top view of the hair clipper of FIG. 8;

FIG. 11 is a front view of same; and,

FIG. 12 is a rear view of same.

The broken lines are shown for illustrative purposes only and form no part of the claimed design.
